VERDOL PAPER

Johann Spahn, Tagerwilen, Switzerland

Application September 18, 1933, Serial No. 690,029
In Germany September 28, 1932

4 Claims. (Cl. 139—333)

This invention relates to a new Verdol paper. It is known that, for operating Verdol jac- guards and other looms which work on a similar principle, perforated paper bands are used. The

5 patterns and designs which are woven are determined by the number and arrangement of the perforations in these bands. These paper bands are usually termed Verdol papers or bands.

Verdol papers have the disadvantage that they 10 expand under the effect of moisture and contract in dry air. These alterations in the surface area are particularly troublesome insofar as they affect the width of the band. The Verdol papers are guided like a cinematograph film by means 15 of pegs or pins which are fixed on a roller, and, if the band expands, it does not lie evenly but becomes undulated, which leads to trouble, since the needles which actuate the hooks either do not enter the holes in the Verdol paper or remain 20 caught in the holes and injure the band. In both cases defects in the fabric result. Further, if the perforations do not come to lie exactly over the needles, they become worn more quickly than usual; the whole band can then become displaced 25 and trouble and defects in the fabric inevitably follow.

Many attempts have hitherto been made to avoid these disadvantages.

The object of the present invention is to provide an improved Verdol paper of which, under the influence of the variation in the moisture in the air, the surface changes are substantially less than heretofore or of which the surface remains practically unaltered in area.

35 According to the invention, a stable Verdol paper is made, for example from an ordinary Verdol paper, by coating it on one or both sides with metal foil. Generally, a coating of foil on one side is sufficient.

40 Especially when using a very thin and cheap paper, the Verdol paper according to the present invention may practically consist of a metal foil coated on both sides with paper, that is to say that the metal coated Verdol paper is provided 45 with a pasted paper layer on the metallic side.

A Verdol paper which is coated with metal foil is substantially insensitive to moisture, that is to say it does not expand in moist air and contract in dry air to any considerable extent, and its area remains substantially unchanged. Further, it has the great advantage of being stronger so that it is not so liable to be torn as the ordinary Verdol papers. Again, a Verdol paper which is 55 coated with metal foil slides better than ordinary Verdol paper.

Aluminum foil is particularly suitable for coating the Verdol paper, since it is both inexpensive and resistant to corrosion.

The coating of metal foil may be attached to the Verdol paper by means of a suitable adhesive.

5 The invention is not limited to Verdol papers properly called so but is also applicable to other perforated papers which are used for a similar purpose, i. e. in machines in which needles contact with the perforations in the paper.

In the accompanying drawing Figure 1 is a face view of a small section of a Verdol paper embodying the present invention. Fig. 2 is a transverse section thereof, and Figs. 3 and 4 are similar sections of modified embodiments.

10 The drawing shows a Verdol paper 10 which may be considered as traveling in the direction of the arrow. This paper has the usual edge perforations 11 for the guidance of the paper through the textile machine and it is formed 15 additionally with numerous perforations 12 which afford the control action on the needles or other instruments of the textile machine.

The Verdol paper is shown as comprising a body portion 13 of paper, which is inherently 20 subject to troublesome distortion of dimension to a substantial extent by reason of natural variations of moisture therein. United intimately upon one side of the paper body in Figs. 1 and 2 is shown the coating of relatively thin metal or 25 aluminum foil 14 which acts not only to strengthen the paper but to fix the paper against substantial alteration of dimensions. Aluminum has the advantage of resisting corrosion and of 30 facilitating smooth travel of the paper or band. 35 It also adds strength, but chiefly, as described, fixes the paper against distortion.

Each band edge may have a stiffening strip 15, preferably at the side opposite to the coating 14; and Fig. 1 may be considered an underneath 40 view, although the band could be used either side up.

In the embodiment of Fig. 3 the Verdol paper 10^a has not only the metal coating 14 on the paper body 13 but also a metal coating 14^a upon the 45 opposite face of the paper.

In the modification of Fig. 4 the Verdol paper band 10^b comprises not only the paper body 13 and the metal or aluminum coating 14 but a second paper layer 13^b overlying the metal coating, which latter is thus confined between the two layers of paper, fixing both of them against troublesome distortion.

Many matters may be variously modified without departing from the principles of the invention.

tion. It is not intended to limit the invention to such matters except to the extent set forth in the appended claims.

What is claimed is:

- 5 1. A Verdol paper, in band or analogous form, for controlling textile machinery, and formed with usual perforations for guidance of the paper and for its control action, the same comprising a body of paper, inherently subject to troublesome substantial distortion of dimension by reason of natural variations of moisture therein, and the surface of such paper body having united to it a coating of relatively thin metal foil, acting both to strengthen the paper and to fix the paper against substantial alteration of dimensions.
- 10 2. A Verdol paper, in band or analogous form, and formed with usual perforations for controlling textile machinery, the same comprising a body of paper, inherently subject to troublesome substantial distortion of dimension by reason of natural variations in moisture therein, and the surface of such paper body having united to it a coating of relatively thin metal foil, and such metal foil being overlaid with a second paper
- 15 layer united thereto, the metal foil, between the

two layers of paper acting both to strengthen the paper and to fix the paper against substantial distortion of dimensions.

3. A Verdol paper, in band or analogous form, and formed with usual perforations for guiding it and for controlling textile machinery, the same comprising a body of paper, inherently subject to troublesome substantial distortion of dimension by reason of natural variations in moisture therein, and the surface of such paper body having united to it a coating of relatively thin aluminum foil, acting both to strengthen the paper and to fix the paper against substantial distortion of dimensions.

4. A Verdol paper, in band or analogous form, and formed with usual perforations for controlling textile machinery, the same comprising a body of paper, inherently subject to troublesome substantial distortion of dimension by reason of natural variations in moisture therein, and both faces of such paper body having united to them coatings of relatively thin metal or aluminum foil, acting both to strengthen the paper and to fix the paper against substantial alteration of dimensions.
